(57) **CLAIM**

The ornamental design for a multi way beach sarong, as shown and described.

DESCRIPTION

FIG. 1 is a front, right, and top perspective view of a multi way beach sarong, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 comprising a fixed ring.

FIG. 9 is a perspective view of the multi way beach sarong of the present disclosure shown in an environment of use thereof.

FIG. 10 is a perspective view of the multi way beach sarong of the present disclosure shown in an environment of use thereof.

FIG. 11 is a perspective view of the multi way beach sarong of the present disclosure shown in an environment of use thereof.

FIG. 12 is a perspective view of the multi way beach sarong of the present disclosure shown in an environment of use thereof.

FIG. 13 is a perspective view of the multi way beach sarong of the present disclosure shown in an environment of use thereof; and,

FIG. 14 is a perspective view of the multi way beach sarong of the present disclosure shown in an environment of use thereof.

The broken lines shown in the drawings depict portions of the multi way beach sarong that forms no part of the claimed invention. The broken lines shown in FIGS. 9-14 showing the human figure and mannequin depict environment and form no part of the claimed design. The line-dash line broken lines in the drawings represent the boundaries of the claim and form no part of the claimed design.

1 Claim, 14 Drawing Sheets
